UNITED STATES PATENT OFFICE.

HENRY FREUND, OF HOUSTON, TEXAS.

FOOTBOARD BRACE.

Application filed September 21, 1925. Serial No. 57,637.

This invention relates to new and useful improvements in a foot board brace.

One object of the invention is to provide a brace of the character described specially 5 designed to support and brace the foot, or running board, of a motor vehicle.

Another object of the invention is to produce a device of the character described which is adjustable so that it may be easily 10 applied and thereafter adjusted as the necessities of the case may require.

With the above and other objects in view this invention has particular relation to certain novel features of construction, operation 15 and arrangement of parts, an example of which is given in this specification and illustrated in the accompanying drawings, wherein:—

Figure 1 shows a side view of a motor 20 vehicle with the brace applied thereto, and

Figure 2 shows an enlarged front elevation of the brace.

Referring now more particularly to the drawings, wherein like numerals of reference 25 designate similar parts in each of the figures the numeral 1 designates the foot board, or running board, of the motor vehicle 2 and the numeral 3 designates the side member of the windshield frame. Two 30 brackets 4 and 5 are provided. These brackets are formed of metal straps bent so as to form tight angularly disposed arms, the horizontal arms fitting against the under and upper sides, respectively, of the 35 running board 1, and being secured in place by the bolt 6, and the vertical arms being

spaced apart as shown. These vertical arms have a space block 7 between them, secured in place by a bolt 6.

A sectional hanger rod is provided consisting of the sections 9 and 10 connected by the conventional turn buckle 11. 40

The upper end of the section 9 has an eye 12 to receive the bolt 13 which secures the frame 3 to the vehicle body. 45

The lower end of the section 10 is also formed with an eye 14 which fits between the upper ends of the upstanding arms of the brackets 4 and 5. A bolt 15 is secured to said upper ends and is fitted through the 50 eye 14.

The brace, when applied may be suitably tightened up by adjusting the turnbuckle 11 and will support and brace, not only the running board but also the adjacent fender 55 as well.

What I claim is:—

A foot board brace for motor vehicles comprising a pair of brackets having upstanding spaced arms adapted to be clamped over the outer edge of a foot board, a brace rod having an eye in each end, one of which is fitted between said bracket arms, a bolt passing through said bracket arms and said eye between them, a bolt passing through the eye in the other end of said rod and into the upper portion of the body and a turn buckle 60 for adjusting the length of said rod. 65

In testimony whereof I have signed my name to this specification.

HENRY FREUND.
